United States Patent Office

Des. 184,831
Patented Apr. 7, 1959

184,831

ELECTRIC ERASER UNIT OR SIMILAR ARTICLE

Joseph Palma, Jr., Wheaton, Ill., assignor to Charles Bruning Company, Inc., Mount Prospect, Ill., a corporation of Delaware

Application June 20, 1958, Serial No. 51,445

Term of patent 14 years

(Cl. D74—7)

FIG. 1

Figure 1 is a side elevation of an electric eraser unit or similar article, showing my new design;

Figure 2 is a front elevation of this electric eraser unit or similar article; and

Fig. 3 is a rear elevation of this electric eraser unit or similar article.

I claim:

The ornamental design for an electric eraser unit or similar article, as shown.
